COPY HOLDER

Franz Bestenreiner, Vienna, Austria

Application February 3, 1958, Serial No. 712,887

4 Claims. (Cl. 120—34)

This invention relates to a copy holder, which enables a linewise displacement of a line pointer on the copy sheet by push button actuation during the copying of a typed copy.

The copy holder according to the invention comprises a plate for supporting the copy, a line pointer, which is vertically adjustable on the plate and pivoted to a carrier, which engages vertical rows of pins on a control shaft, to which a limited angular movement can be imparted by actuation of a push button, said carrier being subjected at the same time to the influence of a spring force which tends to urge the carrier downwardly.

Another feature of the invention resides in that the control shaft comprises a plurality of vertical rows of pins arranged in pairs of adjacent rows, the pins of one row of each pair being spaced in accordance with the line spacing of the copy and the pins of the other row of each pair lying between the pins of the first row and being angularly offset therefrom.

A further feature of the invention resides in that a latch entering between the pins of the control shaft is provided on the carrier of the line pointer and is connected by a Bowden wire to a spring-loaded ratchet mechanism, which is strained during the upward movement of the latch.

Additional features of the invention will be explained with reference to the drawing, which shows an illustrative embodiment of the copy holder according to the invention. Fig. 1 is a side view showing the device, Fig. 2 an end view showing the device of Fig. 2, part of the copy supporting plate and the device for fixing the copy holder to a table being omitted. Fig. 3 is a longitudinal sectional view of the device, taken on line III—III of Fig. 2. Fig. 4 is a transverse sectional view taken on line IV—IV of Fig. 1, the stepping mechanism for controlling the carrier for the line pointer as well as part of the line pointer and of the copy supporting plate being omitted for the sake of simplicity. Fig. 5 is a longitudinal sectional view of the head portion of the stepping device of the copy holder, taken on line V—V of Fig. 6. Fig. 6 is a sectional view of the head portion of the stepping device of the copy holder, taken on line VI—VI of Fig. 5. Fig. 7 is a longitudinal sectional view of the base portion of the stepping device of the copy holder, taken on line VII—VII of Fig. 8, and Fig. 8 is a sectional view taken on line VIII—VIII of Fig. 7. Figs. 3 to 8 are drawn on a larger scale than Figs. 1 and 2.

The copy holder according to the invention comprises a plate 74 (Fig. 2) for supporting the copy. This plate is affixed with screws 84 (Fig. 4) to a housing 8, which carries at its end a guide plate 13 and serves for receiving a control shaft 1. The latter is provided at both ends with journals 2 and 3, respectively. The upper journal 2 is disposed in a bearing 80 (Fig. 5) and extends in a bore 23 through the bottom 21 of the head member 20. That end of the journal 2 which is disposed in the head member 20 has a wing 4, which is guided in a segment-shaped slot 24 (Fig. 6) of the bottom 21 and

2

is subjected to the load of a spring 25, which is hung at one end in the eyelet 5 on the wing 4 and at its other end on a bolt 85 affixed to the bottom 21. This spring 25 tends always to swing the control shaft 1 in the direction of arrows "a." For this reason the wing 4 will always tend to engage the left-hand (when viewed as in Fig. 6) edge of the slot 24. The head member 20 is covered by a cap 29 (Fig. 5), which supports a rotary knob 30. Screws 31, 32 connect the knob 30, the cap 29 and the head 20 to each other. The heads of these screws are countersunk in the knob 30 and their screw threads are threaded in the bottom 21 of the head member 20. The head member 20 is continued by a sleeve 86, which embraces the top end of the housing 8 and terminates in a ring 34, which has notches 87 for receiving a locking device 17. The latter is guided in a cage 88 and urged by a spring 89 into the notches 87. A lever 91, which extends outwardly through the slot 90 of the cage 88, can be depressed to disengage the locking device 17 from the ring 34, whereafter the control shaft 1 can be turned through any desired angle with the aid of the knob 30.

As is shown in Figs. 3 and 4, the control shaft 1 comprises vertical rows of horizontally extending pins 6', which are spaced around the periphery of the shaft. These rows of pins are arranged in pairs of adjacent rows 6, 7. The spacing of the pins of one row, e.g., of the row 6, equals the line spacing of the copy; the pins of the other row 7, which is offset by a small angle from the row 6, are arranged between the pins of the row 6. Because different typewriters have different line spacings, each double row of the pins 6' is dimensioned in accordance with another line spacing.

As is shown in Figs. 1 to 4, a carrier 42 is vertically adjustably provided on the guide plate 13. This carrier is connected by a double joint 57, 58 to a line pointer 56, to which a slight vertical adjustment along a screw spindle 92 can be imparted by means of a nut 59. The carrier 42 has two lugs 50, 51, between which a release member 45 is pivotally mounted on the pin 52. A latch 47 entering between the pins 6' is fitted in the nose 46 of this release member. During the vertical adjustment of the carrier 42 the nose 46 slides in the slot 14 of the plate 13. The guidance of the carrier 42 is assisted by a cam guide 43. This construction requires slots 49 and 48, respectively, to be provided in the cam guide 43 and the carrier 42 as passages for the nose 46. A pulling rope 54 affixed to the lower end 53 of the release member 45 extends around the pulleys 55 and 19 to a ratchet mechanism 75. This mechanism is mounted between the brackets 64, 65, which are affixed with screws 44, 44' to the housing 8 and have cheeks 66, 67 through which extends a bolt 68 having a head 69 and a wing nut 70 for clamping the ratchet mechanism. The latter comprises a drum 76 for winding up the rope 54. This drum is provided with a ratchet wheel 78 and encloses a spiral spring 77. The inner end of this spring engages the stationary bolt 68; the outer end of the spring engages the rotatable drum 76. A pawl 79 is provided for holding the ratchet wheel when the spring 77 is in strained condition.

The cheeks 66, 67 of the brackets 64, 65 are downwardly extended in a tube 71, which is telescopically disposed in a second tube 72 and permits of a rotation of the housing 8 about the central axis of the tube 71. The tubes 71, 72 are fixed in their relative position by a wing screw 73. The tube 72 is provided by means of a lever 93 with a clamp 94, which serves for clamping the copy holder to a table top or the like.

As is shown in Figs. 7 and 8, a base member 35 screwed to the lower end of the housing 8 accommodates a stepping wheel 39, which is secured with a key 40 to

the lower journal 3 of the control shaft 1. The stepping wheel 39 is actuated by the push button 81 by means of a Bowden wire 37 and a control pawl 38. A connecting member 36 for guiding this Bowden wire is provided on the base member 35. The push button 81 may be 5 detachably affixed to the keyboard frame of the typewriter. It is only necessary to dispose it so that it can easily be actuated by the typist.

The copy holder plate 74 may comprise a clip 82 for holding the copy sheet and may have some scales 83, 83a, 83b etc. for ascertaining the line spacing of the copy. The number of scales provided corresponds to the number of line spacings to which the copy holder can be adjusted, i.e., to the number of double rows of pins 6 on the control shaft 1.

The copy holder described operates as follows: The copy is applied to the scales 83, 83a, 83b to find out which scale corresponds to the line spacing of the copy. The pair of pin rows 6, 7 which is associated with the scale that has been found is then brought into registry with the latch 47. To this end the lever 91 is depressed and the knob 30 is rotated until the row of pins 6 of the respective double row is in registry with the latch 47. Then the lever 91 is released to enable the locking device 17 to lock the control shaft 1 in its adjusted position. The copy is then clamped with the clip 82 on the plate 74.

The release member is lifted to move the same in the clockwise sense when viewed as in Fig. 3. This causes the latch 47 to disengage the pins 6'. Thereafter the release member 45 is moved upwardly, moving the carrier 42 and the line pointer 56 along, until the latter is disposed between the uppermost line of the copy. This causes the spring 77 to be strained. When the release member 45 is then released the latch 47 will enter between the next adjacent pins 6', whereby the line pointer 56 is locked in position. If the line pointer lies in its uppermost position slightly below or above the line, the line pointer can be adjusted with the screw 59 to the desired level.

The linewise downward movement of the line pointer 56 is effected by actuation of the push button 81. The depression of this push button causes through the intermediary of the Bowden wire 37 the pawl or wedge 38 to be advanced in the direction of the arrow "b," whereby the stepping wheel 39 and the control shaft 1 connected thereto are rotated in the clockwise sense, when viewed as in Figs. 6 and 8, until the wing 4 engages the right-hand edge (when viewed as in Fig. 6) of the slot 24. At this time the pin, e.g., of the row of pins 6 (Fig. 4), which previously supported the latch 47 has left the latch 47 and the next lower pin of the row of pins 7 has entered below the latch 47. The strained spring 77 pulls the carrier down onto this lower pin of the row 7. When the push button 81 is released the spring 25 pulls the control shaft 1 back to its initial position; at the same time the wedge 38 returns to its initial position. During this movement the pin of the row of pins 7 has left the latch 47 and has been replaced by the next lower

pin of the aforementioned row 6. During the forward and backward swing of the control shaft 1 caused by a single depression and release of the key 81 the latch has moved from one pin of the row of pins 6 to the next; at the same time the line pointer has moved to the next lower line. This operation is repeated for every shifting of the line pointer to the next line.

What is claimed is:

1. An improved copy holder comprising a base plate, means for holding said base plate on a desk adjacent to a typewriter, means for holding the sheet to be copied on the base plate, a housing disposed along a vertical edge of the base plate, a line pointer movable along said base plate, a control shaft rotatably mounted in said housing and provided with radially protruding pins, said pins being arranged in a number of rows which extend parallel to the axis of the control shaft, said rows of pins being arranged in pairs around the periphery of the control shaft, a carrier guided along the housing and holding the line pointer and pivoted to and moved with said line pointer, a latch connected to the carrier and entering between and controlled by the pins of the control shaft, spring-loaded means for pulling said carrier in the direction toward the bottom edge of the base plate, and operating means for oscillating the control shaft through an angle which corresponds to the angle between any two rows of pins forming a pair.

2. A copy holder as claimed in claim 1, characterized in that said control shaft has the pins of one of the two rows forming a pair angularly spaced between the pins of the other row, a toothed stepping wheel at the lower end of said control shaft, a wedge interengaged with said stepping wheel, hand operable means for pushing said wedge forward for rotating the control shaft.

3. A copy holder as claimed in claim 1, characterized in that the housing for rotatably mounting the control shaft comprises at its top end a rotatable part having a knob for adjusting the control shaft, a releasable locking device, the rotatable part having a stepping wheel interengaged with said releasable locking device, a bottom formed with a segment-shaped slot to limit the angular movement of said control shaft to the angular size of said slot.

4. A copy holder as claimed in claim 1, characterized in that the carrier comprises a pivoted release member which directly carries the latch entering between the pins of the control shaft and is slidable in a longitudinal slot of the housing, a Bowden wire connected to the release member, a ratchet mechanism for winding up the Bowden wire and a spring which loads the ratchet mechanism and is strained when the Bowden wire is pulled away from the ratchet mechanism.
